ATTORNEY

UNITED STATES PATENT OFFICE.

HANS H. H. HARKLOW, OF FREEPORT, NEW YORK.

DERRICK.

Application filed August 31, 1920. Serial No. 407,140.

To all whom it may concern:

Be it known that I, HANS H. H. HARKLOW, a citizen of the United States, residing at Freeport, in the county of Nassau and State 5 of New York, have invented new and useful Improvements in Derricks, of which the following is a specification.

This invention relates to derricks and in particular to what are known as "stiff-leg" 10 and "guy" derricks, and the principal object is to provide a device of this nature in which a wooden and steel derrick may be constructed in sections.

Another object is to provide an improved 15 revolving mast step so as to do away with the use of "bull-wheels" and tag ropes.

Another object is to provide the mast with mounting means so that the mast may be set in close to the wall of a building in operation. 20

Another object is to provide an improved splicing means for the members of the derrick.

Another object is to improve the supporting construction. 25

Another object is to render the sheaves at the bottom of the mast, readily accessible.

Other objects will appear from the following description and claims. All of these 30 objects are attained by the means shown in the accompanying drawing comprising two sheets, in which:—

Figure 1 is an elevation view of my improved derrick.

Figure 2 is a fragmentary detail view 35 illustrating the manner of splicing the members of the derrick.

Figure 3 is a sectional view taken substantially on line 3—3 of Figure 1.

Figure 4 is a vertical sectional view 40 through the mast step.

Figure 5 is a plan view of the mast step.

Figure 6 is a vertical sectional view taken substantially along line 6—6 of Figure 4. 45

Like characters of reference refer to like parts in all views.

Heretofore wooden derricks have been made with the mast, brace, boom and sill each in a single piece and have caused considerable trouble in moving from place to place on account of their size and weight. Derricks are transported from one place to another in the city on what are known as 50 reach trucks and if the members are excessively long the rear wheels may skid and cause the timbers to swing into a building 55

or the like when it is attempted to turn a corner. In transportation upon the railroads the length of the members has often required two or three flat cars to be used 60 for transportation. Furthermore there has been great waste and inconvenience in replacing broken parts. It is the purpose of this invention to construct a wooden derrick in sections so that the same may be easily 65 loaded upon an ordinary wagon or placed in box cars and any one of the parts of which may be readily and economically replaced in case of damage. The other purpose of the present invention is to place the 70 derrick in a mechanical control so as to do away with the bull-wheel which is now in use and to avoid placing the lives of operators in jeopardy by the use of tag ropes.

Referring more particularly to the drawings, 1 represents the sections of the sills of a derrick embodying my invention, 2 represents similar parts of the braces and 3 similar parts of the mast. The sections in each case are spliced together as will be 80 presently specifically described so as to form rigid members. The upper end of the mast is provided with a thrust ball-bearing at 4 and upon this are mounted the goose-neck fittings 5 on both of the braces, each brace being secured at its lower end to the respective sill by a brace fitting 6. 7 and 8 represent topping lift tackle blocks by means of which the live boom is raised and lowered. 90 This live boom is composed of several sections 9 which are spliced together in the same manner as the before mentioned members. Tackle and hoisting blocks are shown at 10 and 11 and the co-operating cable 12 of said blocks 10 and 11 passes over a sheave 13 in one of the members 9 and then down over a sheave 14 mounted on the mast. The cable 15 which co-operates with blocks 7 and 8 passes down over sheaves 16 and 17 as shown in Figure 1, and in rear of a 95 sheave 14 mounted on the same rod as the sheave over which the cable 12 passes.

The manner of splicing the various members is fully shown in Figure 2, in which a splice of the members 2 is shown. The members 2 abut against each other at 18 and are cut away to fit into channel bars 19 and are bolted in place by bolts 20 which pass through the channel members 19, the members 20 and through a spacer 21. When the 105 member is to be subjected to compressing stress as for instance in the mast the mem- 110

bers 21 are made sufficiently long to entirely fill the space between the side members of a splice.

The sheaves 14 are mounted between plates 22 as shown in Figure 3, which plates are secured to respective angle irons 23. Bolts 24 pass through angle irons 23, and the mast and through a plate 25 on the opposite side of the mast to secure the support 10 in place.

In the present invention the mast is supported at its lower end in a chamber 26 formed in the mast step 27 and the boom is pivoted in a chamber 28 of said step. To the 15 base of the member 27 is bolted or otherwise secured a member 29 having on its periphery gear teeth 30 adapted to mesh with a gear pinion 31. A standard 32 carries a thrust ball bearing 33 upon which the member 29 20 is seated. Member 29 is provided with a downwardly projecting portion 34 which fits into a socket 35 in the member 32, and is secured therein by a plurality of bolts 50 which have their inner ends entered in an 25 annular groove 51 in 34. The member 32 is supported upon four I-beams 36 which are arranged in pairs. Mounted upon these I-beams is a stub shaft 37 upon which pinion 31 is secured, and to said shaft 37 is also 30 secured a gear 38 which may be operated from an electric motor or from any other source of power. The I-beams 36 are secured to the sills and the inner ones of these I-beams are provided as shown in Figures 5 35 and 6 with inwardly facing bearing blocks 39 having bearings 40 for a rod upon which are pivoted sheaves 41 over which the cables 12 and 15 are passed on their way to the motor or engine or any other source of power. The blocks 39 are held in place by 40 flanges 42 and 43 and blocks 44. Flange 42 is formed on a member 45 and flange 43 on a member 46 and both are held in place by bolts 47 which pass through the I-beams and 45 coact with sleeves 48 to hold said I-beams in spaced relation as shown in Figures 5 and 6. The block 44 is held in place by a bolt 49, and it will be obvious that if one of the sheaves 41 is broken it may be readily replaced by merely removing the two bolts 49 and slipping the pivot blocks 39 out.

The I-beams 36 are held to the member 32 by means of bolts 50 which pass through the apertures between the pairs of I-beams and clamp square plates 51 against the inner faces of the upper flanges as shown in Figure 6.

It will be readily seen that every movement of the derrick is under mechanical control, and that by making the revolving mast

step so compact the device can be set in close to a building wall for use. It will also be noted that all parts are readily accessible and that by this construction the derrick may be quickly and easily transported from one 65 place to another.

While I have described what I deem to be the most desirable embodiment of my invention, it is obvious that many of the details may be varied without in any way departing 70 from the spirit of my invention; and I therefore do not limit myself to the exact details of construction herein set forth nor to anything less than the whole of my invention limited only by the appended claims. 75

What I claim as new and desire to secure by Letters Patent is:—

1. In a device of the class described, the combination of a plurality of beams secured together in pairs and in spaced relationship with each other, a socket member supported by said beams, a bearing supported by said socket member, a mast support rotatably supported by said bearing and provided with an element adapted to project into the socket 85 of said socket member, and mechanical means for driving said mast support.

2. In a device of the class described, the combination of a plurality of beams secured together in pairs and in spaced relationship with each other, a plurality of removable bearing blocks mounted on said beams, a pivot rod mounted in said blocks, and a sheave mounted on said rod. 90

3. In a device of the class described, the combination of a plurality of beams secured together in pairs and in spaced relationship with each other, a plurality of removable bearing blocks mounted on said beams, a pivot rod mounted in said blocks, a sheave 100 on said rod, a socket member rigidly supported by said beams, and a mast supporting member rotatably mounted on said socket member. 95

4. In a device of the class described, the combination of a plurality of beams secured together in pairs and in spaced relationship with each other, a plurality of removable bearing blocks mounted on said beams, a pivot rod mounted in said blocks, a sheave on 110 said rod, a socket member rigidly supported by said beams, a mast supporting member rotatably mounted on said socket member, and a mast supporting member rotatably mounted on said socket. 115

In testimony whereof I have affixed my signature.

HANS H. H. HARKLOW.
